UNITED STATES PATENT OFFICE.

GILBERT R. ELLIOTT, OF BOSTON, MASSACHUSETTS, ASSIGNOR OF ONE-HALF TO MILTON CLARK, OF SAME PLACE.

WIRE CARRIAGE-WAY.

SPECIFICATION forming part of Letters Patent No. 276,529, dated April 24, 1883.

Application filed March 29, 1883. (No model.)

To all whom it may concern:

Be it known that I, GILBERT R. ELLIOTT, of Boston, in the county of Suffolk and State of Massachusetts, have invented certain new and useful Improvements in Wire Carriage-Ways, of which the following is a full, clear, and exact description.

My invention relates to improvements in that class of devices for transporting and carrying articles from one point to another, and means for checking or stopping the carrier as it reaches its destination with as little shock or noise as possible; and it consists of a suspended car or carrier supported by grooved wheels suspended on an elevated cable-wire or wire rope, covered or not, and said carrier being formed in two parts, the lower suspended by toggle-link and springs from the upper.

The objects of my improvements are to construct a car or carrier having an upper platform or covering and a bottom tray, which are adapted to be brought in contact with each other automatically, and thus prevent any article therein contained from falling out; to provide an adjustable stop or check block having an inclined plane and hollow rest for the wheels of the carrier, and a head or buffer to prevent shock. I attain these objects by the mechanism illustrated in the accompanying drawings, in which—

Figure 1 is a horizontal side view of my improvement. Fig. 2 is a vertical front view of the car or carrier. Fig. 3 is a perspective view of the tray; Fig. 4, a perspective view of the toggle-link; Fig. 5, a side view of the stop or check block and rest; Fig. 6, a vertical face view of the same, and Fig. 7 a view showing a longitudinal section of the protected or covered cable or wire.

Similar letters refer to similar parts throughout the several views.

The horizontal suspended wire cable A, which is secured to suitable supports, (not shown in the drawings,) is covered by vulcanized rubber or any suitable material, for the purpose of preventing or deadening the noise of the passing carrier. This cable A is adapted to support a carrier, C, which is constructed as follows: Said carrier is suspended by means of grooved pulleys D D, connected to the upper platform or covering, E, by hangers D' D'. To the covering-lid E are pivoted toggle-links G G G G,

two on each side of the carrier, (I do not, however, limit myself to that number, as more or less may be used when found advantageous,) 55 the other ends of the toggle-links being attached to a tray, H. These toggle-links may be made very light and of sheet metal. They can also be constructed of different thicknesses, as the case may require. This tray or box is protected when closed (being its normal position) by the covering-lid E, which is made slightly longer and wider than the tray, so as to extend over the rim or border H'. Each pair of the pivoted toggle-links G are connected by 65 means of a rod, J, around which is a spiral spring suitably connected and secured on one side to the upper toggle-links and on the other to the lower toggle-links. To the under part of the tray is secured a ring or handle, I, the 70 purpose of which will more fully be described hereinafter.

On the cable A is secured an adjustable stop or check block, M, composed of two depending arms, R, which are adapted to fit over the cable A, and under which they are united by means of screws or bolts S. The forward part of the stop or check block M forms an inclined plane, N, then by curving downward, as shown at O, forms a seat, O', for the reception of the 80 grooved wheel, and then by curving upward forms a buffer, Q, to which is attached a suitable elastic material, P, the purpose of which will be hereinafter more fully described.

The operation is as follows: The adjustable 85 stop or check block having been suitably secured in its position on the cable, and the carrier also suspended from the same, the operator pushes the carrier over the cable, its velocity carrying it up the inclined plane N until one of 90 wheels D falls into the seat O, being there arrested from further movement by the curvature of the seat. Now, supposing the tray or box is closed—*i. e.*, in contact with the cover E, as shown by dotted lines—the operator wishing to load simply takes hold of the ring I and lowers the tray to any desired level, the spring on the toggle-link C allowing of this movement. To shut the tray all that is necessary is to let go the ring I, when by the tension of 95 the springs it will return in place. Other means of carrying the tray to the cover may be employed which would be within the range of my invention.

The broad subject-matter of the combination, in a carrier for transporting packages, of a frame suspended from wheels adapted to a cable or wire rope, and provided with a platform and an adjustable tray, is withdrawn for the purpose of embodying in it a separate application.

Having thus described my invention, what I claim is—

- 10 1. The combination, in a carrier, of a frame composed of a platform, E, and movable tray H, having a ring, I, toggle-links G, provided with spiral springs K, and rods J, substantially as described.
- 15 2. The combination, in a carrier, of a frame provided with a covering or platform, E, bottom tray, H, provided with a ring, whereby the tray can be opened, spiral spring K, rod J, and toggle-links G, whereby the carrier is
- 20 automatically closed.

3. The combination, in a parcel-carrier, of the suspending-wheels and platform E, the toggle-links, and the tray adapted to be operated by suitable springs for automatically closing the tray and platform together, as described. 25

4. As an article of manufacture, a combined check, seat, and bumper formed with the incline plane N, rest O, and bumper P, as described. 30

In testimony whereof I have hereunto set my hand in the presence of two subscribing witnesses.

GILBERT R. ELLIOTT.
